UNITED STATES PATENT OFFICE.

GEORGE E. MARLATT, OF PASADENA, CALIFORNIA.

TYPOGRAPHICAL DISTRIBUTING MACHINE.

Application filed November 13, 1926. Serial No. 148,306.

My invention relates to typographical machines of the kind employing matrices which are released from a magazine in the assembling operation and restored to their individual channels in the magazine from which they were released following their use in a casting operation. In such machines it is common practice to employ many matrices of miscellaneous character not represented on the keyboard and not stored in the channels of the magazines. These are known as sorts matrices and are inserted in the assembler by hand. Following their use they are released from the usual distributor bar at a common point and descend through a tube to a common storage tray or stacker. My object is to provide a simple device whereby these sorts matrices may be returned to individual positions in several receptacles, one for each font size of sorts matrices, in order that they may be readily located and removed from their storage place when needed.

In the accompanying drawings:—

Figure 1 is a front elevation showing my improvement located at the right hand side of a linotype keyboard, and includes a fragment of the delivery tube leading from the usual distributor bar; Fig. 2 is a section on the line 2—2 of Fig. 1; Fig. 3 is a section on the line 3—3 of Fig. 1; Fig. 4 is a section on the line 4—4 of Fig. 1.

Referring to Fig. 1 the matrices X drop from the distributor bar A into a tube B in the well known manner. From the tube B they enter a primary opposed-groove channel C formed in opposed plates D, E of this invention. The matrices have font-separating notches X¹ occupying various positions on the ends of the matrices according to their font size or style. The position and shape of this font notch determine and control the release of the matrices from the primary channel C to various branches (1 to 9) thereof. At the junction of each branch channel with the primary channel I place a font-distinguisher point F. In each of its occurrences this font distinguisher projects from a block G, and these blocks serve to space apart the channel plates D, E. At their lower ends G¹ these blocks G are shaped to conform to the V-notch in

which the matrix distributing teeth X² are formed. Each branch channel is sub-branched as at 7^a, 7^b where it joins the primary channel C. The upper sub-branch 7^a receives the upper lugs X³ of the matrices and the lower sub-branch 7^b receives the lower lugs X⁴ of the matrices. If the font notch X¹ does not correspond in position with the font distinguisher F, the matrix will be supported on the font distinguisher and its lower lugs X⁴ will not enter their channel 7^b; nor will the upper lugs X³ enter their channel 7^a in such case, because since the matrix does not tip these upper lugs will bridge the mouth of their channel 7^a. It will be noted that upper ends of the blocks G project above the floor of the channel C while the distinguisher (as at F¹) extends angularly from the upper and outer edge of the block G to a position flush with the floor of the channel C; therefore, if the font notch on the matrix corresponds in position with the font distinguisher the matrix will be stopped against the block G; otherwise, the matrix will rise on the angular distinguisher and pass thereover to an appropriate channel therebeyond. If, however, the matrix is stopped against the block (G¹, for example) it will be unsupported by the distinguisher F¹ and its lower lugs will immediately enter their channel 7^b; the matrix will then turn on its upper lugs X³ as a pivotal point and when these upper lugs reach their channel 7^a they will enter therein and the matrix will be conducted to and through its channel 7. The foregoing description of the entry of a matrix into the channel numbered 7 will apply to any of the channels (1 to 9) and branches thereof. It will be noted that channels 3 and 4 are branches of a common channel 34, and channels 8 and 9 are branches of a common channel 89. In these instances the channels 34 and 89 function in the same manner as does the primary channel C, but the matrices destined for the channels 3, 4, 8, 9 have two font notches, one for releasing them from the primary channel C and a second notch for releasing them into the channels 4 or 9 as the case may be; likewise, the blocks G at the junction of channels 3 and 4 and 8 and 9 are provided with two font distin-

guishers, one of which corresponds in position with the font distinguisher adjacent the primary channel C. In this manner any of the channels may be further branched and the system extended to meet any requirements. The font notches X¹ may be leveled as shown on certain matrices in order that they may best serve their purpose.

The pins G² which support the blocks G have plain ends bearing in the channel plates D, E, hence the blocks and distinguishers are transposable in position for the purpose of directing selected matrices to selected channels. The front plate E is supported on these pins G² and other pins and is held in position by means of threaded latches E¹, E², hence is readily removable for any purpose. The pins G² have a driving fit in the blocks G, hence the blocks are shoulders on the pins and serve to space apart the side plates D, E; also, the pins G² fit tight in the rear plate D in order that the blocks will retain their position when the front plate E is removed.

While the foregoing description of the separation of matrices into fonts by gravity has been confined to sorts matrices, it will be evident that the same system could be employed for separating matrices destined to different channeled magazines each having a separate distributing system including the distributing bar A and the usual distributing screws (not shown). Any such use is intended to be comprised within the scope of my invention.

When employed in connection with the sorts storing device to be described, the channeled font-separating box of the foregoing description may be secured in any suitable manner to the frame Z of the machine with which it is used. It is provided with an adjustable end-closing slide H having an opening I which may be made to register with a selected channel (1 to 9). To this end, the slide H is supported on brackets J having a retaining bead J¹ in engagement with a groove H¹ across the under edge of the slide H. The vertical portion of the slide H is guided between the back plate D and brackets K secured thereto; as thus mounted the slide H is capable of horizontal adjustment in order to register the opening I with a selected font-separating channel. Matrices which have entered a previously used channel after an adjustment has been made will be supported as illustrated in channel numbered 4 and will thus remain until the opening I is again registered with their channel. The matrices pass through the opening I and enter a sorts stacker associated, selectively, with a particular channel above the opening I, but a single stacker may be associated with more than one channel; for example, one end of a stacker may receive matrices from one channel and the

other end thereof from another channel. Thus the six stackers illustrated would serve in connection with the nine channels, if certain ones thereof were used in connection with two channels as explained.

The stackers or trays L are open at their top to permit the entry of the matrices and are open in front to permit the removal of the matrices when required for use. The floor of each stacker has a longitudinal rib L¹ corresponding in position with the font notch of the matrices intended to be stored in a particular stacker; hence any matrices which have entered a wrong stacker will be held in raised position on this rib L¹, indicating that they belong in some other stacker. The stackers hang on studs M¹ projecting from facing sides of the end members M of a rotatable carrier, the end members M of the carrier being rigid on a tubular shaft N. The carrier as thus constructed is mounted for rotation on a rigid shaft O supported in any suitable manner from the frame of the machine employing the stackers. The shaft O is provided with a longitudinal groove O¹ which is engaged by a tongue P¹ on a block P to which is secured a spring Q. When the carrier is rotated to a selected position in order to place a selected stacker in operative position beneath the slide H, this spring Q engages one of a series of detent depressions M² in one of the end members M, thus holding the carrier in a selected position.

In order that the block P to which the spring is secured may be caused to move longitudinally on the shaft O with the carrier, it is secured to a disc R which is held against the end member M by means of a pair of keepers S. As thus constructed, the tongue P¹ prevents the spring Q and disc R from rotating, while the keepers S rotate with the members M but cause the spring to remain in engagement with the carrier, when it is moved longitudinally on the shaft O. The purpose in view in rendering the carrier longitudinally movable is to position any particular matrix in an operative tray L just beneath the channel associated with such tray. Since it is necessary to part or open up the stack of matrices in order to remove a selected matrix, the matrix will therefore return to the stack opening from which it was removed provided such opening is placed beneath an appropriate channel. Therefore any matrix taken from any selected tray or stacker will return to its appropriate place provided the precaution is taken to remove it only after the carrier has been rotated and moved endwise to place the matrix beneath the channel through which it will return. If such precaution is not taken beforehand, the slide H and font-distinguishing rib L¹ will serve as explained to notify an operator of a mixed condition of the matrices.

An adjustable 130

spring stop T serves to support the stack of matrices in the event that a stacker is only partly filled with matrices.

Having thus described my invention, its use and advantages, what I claim as new and desire to secure by Letters Patent, is:

1. In a typographical distributing machine, in combination with matrices having font notches in various positions thereon according to font, a channeled font-separating box through which said matrices move by gravity, and means for directing certain matrices to certain channels therein, said means consisting of font distinguishes capable of controlling the entry of said matrices into proper channels according to their position relative to the planes of the font notches on said matrices.

2. In a typographical distributing machine, in combination with matrices having font-separating notches in various positions thereon according to font, a font-separating box having communicating opposed-groove channels therein, and means for directing said matrices to an associated channel as determined by the position of the font notch thereon, said means comprising a font distinguisher at the mouth of each of said channels and occupying a position corresponding to the position of the font notch on matrices destined for an associated channel, whereby matrices so destined will be permitted to enter their channel while other matrices will be rejected by said font distinguisher and caused to pass thereover.

3. In a typographical distributing machine, in combination with matrices differentiated according to font, a font-separating box having a separate channel for matrices of each different font, and a tray for receiving matrices from certain of said channels, means for preventing matrices from other channels from entering said tray, said means comprising a closing member H at the discharge end of said channels having a single opening I therethrough and being adjustable relative to said channels in order to register

said opening with a selected channel so that matrices may pass from such selected channel through said opening and into said tray. 50

4. In a typographical distributing machine, in combination with a tray for storing sorts matrices and a channel through which said matrices are conducted to said tray, means for causing said matrices to enter individual positions in said tray, said means consisting in rendering said tray adjustable longitudinally relative to said channel, whereby that position in said tray from which an individual matrix is removed may be caused to register with said channel in order that said matrix may be caused to return thereto through said channel.

5. In a typographical distributing machine, in combination with matrices differentiated as to font and individual trays for matrices of individual font, means whereby said matrices may be caused to enter a selected tray from a common plane, said means consisting in suspending said trays in a rotatable carrier, whereby a selected tray may be carried to a position beneath the plane from which said matrices are delivered.

6. In a typographical distributing machine, a combination as specified in claim 5, including also means whereby said rotatable carrier is adjustable longitudinally in order that individual positions in selected trays may be caused to register with a common point in said common plane, for the purpose specified.

7. In a typographical distributing machine, in combination with sorts matrices having font distinguishing notches in various positions thereon according to font, a tray for matrices of each font, and a font-distinguishing rib L¹ across the floor of said tray in a position to co-operate with the font notch of matrices intended to be stored in said tray.

Signed at Pasadena, Los Angeles County, California, this 4th day of November, 1926.

GEORGE E. MARLATT.
